UNITED STATES PATENT OFFICE.

ANDREW A. KUCHER, OF CHESTER, PENNSYLVANIA, ASSIGNOR TO WESTINGHOUSE ELECTRIC & MANUFACTURING COMPANY, A CORPORATION OF PENNSYLVANIA.

REFRIGERATOR.

Application filed July 10, 1923. Serial No. 650,667.

My invention relates to refrigerating machines, particularly to small capacity machines of the compression type which are suitable for household use and it has for an object to provide apparatus of the character designated which shall include simple and effective means for compensating for the working fluid which may escape from the condensing chamber, and for exhausting the air which may enter the condensing chamber. Furthermore, it has for an object to provide a brine tank which may be readily removed from the refrigerator box and which has associated therewith an evaporator of such design as to provide a maximum amount of heat-absorbing surface consistent with the space occupied.

These and other objects, which will be made apparent throughout the further description of the invention, may be attained by the employment of the apparatus hereinafter described and illustrated in the accompanying drawings in which: Fig. 1 is a view partly in section and partly in elevation of a compression refrigerator in which my invention may be practiced; Fig. 2 is a plan view taken on the line II—II of Fig. 1; Fig. 3 is a plan in section taken on the line III—III of Fig. 1; Fig. 4 is a view in sectional elevation of a preferred type of evaporator and Figs. 5 and 6 show alternative types of construction for housing the motor and the compressor.

Refrigerators having the motor and the compressor tightly encased within the condensing chamber have, in some instances, been provided with suitable access means for permitting periodic inspection of the motor. However, from continued removal of the access means, there results eventually a considerable loss of working fluid, which usually cannot be compensated for except by recharging the machine in the original way.

In my improved apparatus, provision is made for inserting within the condensing chamber, upon removal of the access means, such additional working fluid as is required to compensate for that lost incident to each inspection of the motor. Furthermore, adequate provision is made for removal of the air admitted. In this manner, a machine may be operated indefinitely, without incurring any substantial loss of working fluid. In addition thereto, the brine tank in my apparatus is so constructed and arranged as

to be capable of being easily removed from the refrigerator box, thereby facilitating recharging of the tank and cleansing of both the tank and the outer heat-conducting surfaces of the evaporator. My preferred form of evaporator is constructed of coils of tubing combined with a cylinder arranged concentrically within the coil, said cylinder occupying space which it has been customary heretofore not to utilize in evaporators of the coil type. The combination of the cylinder and the coil produces an evaporator, which, I believe, provides a maximum amount of heat transfer surface consistent with the space occupied.

Referring to the drawings for a more detailed description of my invention, I show the condensing chamber of a refrigerator of a type disclosed in my copending application, serially numbered 509,672, filed October 22, 1921, and entitled "Refrigeration machine". It is to be understood, however, that my invention may be practiced in other types of compression machines and that the apparatus illustrated and herein described is employed by way of example and as an aid in presenting a clear exposition of my invention. As illustrated, 10 designates a portion of a refrigerator box. Supported thereon is a condensing chamber 11, surrounded by a casing 12 composed of material similar to that of the outside portions of the refrigerator box. This casing considerably improves the appearance of the apparatus and makes inaudible the rather small amount of operating noise. The condensing chamber 11, comprises a bell or dome 13 secured to a base plate 14 as by bolts 15. Disposed within the condensing chamber 11 and supported upon the base plate 14 is a motor 16 provided with a casing 17. A portable plate 18 is suspended by bolts 19 from the base plate 14 and permits access to the motor casing. Supported upon the portable plate 18 is a plurality of commutator brushes 21 and a receptacle 22. Current is supplied through a control panel 23, which is housed within and supported from the casing 12, to the conduits 24 and thence through fluid-tight plugs 25 to the motor.

Superimposed upon the motor casing 17 is a compression mechanism 20 of the type disclosed in my copending application, serially numbered 599,019, filed November 4, 1922, and entitled "Refrigerating apparatus". It is composed principally of a rotor 26 and a

casing 27. The rotor 26 is connected to the motor by means of a shaft 28. An end sealing plate 29, which is subject to the discharge pressure of the compression mechanism, is provided. A weak spring 31 and a pin 32 help maintain the sealing plate 29 in axial alignment and guard against displacement during shipment of the apparatus. A check valve 33 is provided in the discharge passage 10 of the compression mechanism for preventing a back flow of the refrigerant vapor during non-operation of the apparatus.

A purge valve 34 is provided in the highest portion of the dome 13. Disposed in the upper portion of the condensing chamber 11 is a plurality of condensing coils 35 having an inlet connection 36 and an outlet connection (not shown) which pass without the chamber. Provision is made for connecting flexible hose 20 to these connections for conveying a cooling medium from some extraneous source.

Disposed within the refrigerator box 10 is an evaporator 38 which communicates through the conduit 39 with the condensing chamber 11 for the passage of liquid working fluid. The flow of the liquid through the conduit 39 is controlled by means of a reducing valve 41. The reducing valve 41 is actuated by a float mechanism composed of metal bands 42 secured to a float 43 composed of some suitable material such as wood. The wood may be covered with a phenolic condensation product 44 which I have found is impervious to such refrigerants as ethyl 35 chloride. It is generally agreed that a wooden float is cheaper to manufacture than one fabricated from metal but it is subject to the objection, however, that eventually the wood becomes saturated with the liquid, resulting in an alteration of its specific gravity. By applying a heavy coating of the character indicated to the wood, it is unaffected by the surrounding liquid, and performs equally as well as the more costly metal floats.

Disposed within the evaporator 38 is a vapor outlet conduit 45 having its inlet end 46 disposed above the level of the liquid working fluid and having a portion thereof 47 disposed well below the level of the liquid. In this portion, a small aperture 48 is provided for the admission of a limited quantity of liquid working fluid into the refrigerant vapor. The remaining portion of the conduit 45 is formed into a coil 49 which communicates with the return conduit 51. The return conduit 51 is arranged concentrically without the supply conduit 39, thereby eliminating unnecessary joints. It rigidly supports the evaporator 38 from the condensing chamber. The return conduit 51 communicates with the inlet port of the compression mechanism through the passage 52. It further communicates with the interior of the motor casing 17 through a passage 53 for the removal therefrom of refrigerant vapor

and liquid working fluid which may leak into the same. A check valve 54 is provided in the passage 53 for preventing a back flow of the working fluid.

Disposed within the refrigerator box 10 is a brine tank 55 having an opening 56 provided in the upper portion for the admission of the evaporator 38. A depending flange 57 surrounds the evaporator and extends within the tank to reduce the possibility of spilling brine by moving the refrigerator. A plurality of hooks 58 engage the upper surface of the box by means of the nuts 59 and sleeves 61. They may be freely rotated by hand and support two rods or shafts 62, which are secured to the upper surface of the brine tank by suitable brackets 63. A plurality of drawers 64 for the manufacture of ice are provided within the brine tank.

The operation of the apparatus thus described is as follows: The condensing chamber 11 and the evaporator 38 are filled to a level, such as indicated on the drawing, with a suitable working fluid. The working fluid generally employed in my apparatus is a combination of a refrigerant and a lubricant which readily mix one with the other to form a homogeneous mixture or physical solution and which I disclosed in a copending application of mine serially numbered 617,844, filed February 8, 1923 and entitled "Refrigerators". This working fluid is of such character that its constituents are not separable mechanically but only by vaporization. The tank 55 is filled to a level, such as indicated, with brine.

Upon starting the motor 16, the compression mechanism 20 discharges past the check valve 33 into the condensing chamber 11 a refrigerant vapor having entrained therein a quantity of liquid of high lubricating quality. The refrigerant vapor is condensed upon the coils 35, through which is being circulated a cooling medium, and falls to the lower portion of the condensing chamber. Upon sufficient accumulation of liquid working fluid in the condensing chamber, the float 43 will move to open the reducing valve 41 to permit the liquid to flow through the conduit 39 to the evaporator 38. Cold is then produced in normal manner by the absorption of heat from the brine in the brine tank 55 and the vaporization of the refrigerant contained in the liquid working fluid. The brine in turn absorbs heat from the relatively warm refrigerator box, and, upon sufficient reduction in temperature therein, automatic devices provided within the control panel 23, stop the motor.

The refrigerant vapor generated within the evaporator accumulates in the upper portion thereof and is removed through the conduit 45. It enters the upper portion of the conduit as at 46 and flows downwardly through the submerged portion 47. A small

amount of liquid working fluid enters the conduit through the aperture 48 and becomes entrained in the refrigerant vapor. The refrigerant vapor having entrained therein a small quantity of liquid working fluid passes upwardly through the coil 49 and absorbs additional heat. This additional heat is sufficient to vaporize off most of the refrigerant present in the entrained liquid and consequently the refrigerant vapor which enters the return conduit 51 has entrained therein a quantity of liquid of high lubricating quality. This mixed vapor and liquid is drawn upwardly through the passage 52 by the compression mechanism and the liquid serves to lubricate the working parts of the latter in passing therethrough. This completes the cycle of operation which may then be repeated. A very effective end seal for the compression mechanism is maintained by the plate 29, which is subject to the discharge pressure. If at any time, an amount of liquid in excess of the volumetric displacement of the compressor should attempt to pass through, the excess liquid is relieved between the plate 29 and the end face of the rotor 26, thereby avoiding stoppage of the motor.

If in the course of operation, it becomes advisable to inspect the commutator brushes of the motor, the bolts 19 may be removed and the plate 18, together with the brushes 21 which are supported thereon, lowered. If found necessary, new brushes may be installed and the plate replaced. During the removal of the plate, however, the refrigerant vapor present in the motor casing 17 escapes to the outside atmosphere and there is an inrush of air. To compensate for the lost refrigerant, the receptacle 22 may be filled to the required level with liquid refrigerant and, upon the plate 18 being replaced and the motor started, the air present in the motor casing will be withdrawn through the opening 53. Upon sufficient reduction in the pressure prevailing within the motor casing, the liquid refrigerant contained in the receptacle 22 vaporizes and thereby compensates for the refrigerant vapor lost during the inspection of the commutator brushes. The air drawn in by the compressor is discharged into the condensing chamber, wherein it rises to the upper portion and may be purged off through the valve 34. With the above apparatus, not only may sufficient refrigerant be inserted to compensate for the losses mentioned above, but such additional fluid may be added at that time as is required to compensate for all prior losses which may have occurred during the normal operation of the apparatus.

Should it become advisable at any time to thoroughly cleanse and recharge the brine tank 55, it may be readily removed from the refrigerator box 10 by raising it slightly upward and turning the supporting hooks 58

about 90°, whereupon the tank may be lowered free of the evaporator 38 and removed from the box. This permits of a thorough cleansing of the outer surface of the evaporator, thereby freeing it of any material which may decrease its heat conducting qualities. As it is very desirable to maintain the interior of refrigerator boxes of this type in a highly pleasing and sanitary condition, I have found the above arrangement to be a very valuable one.

Fig. 4 illustrates a preferred form of evaporator which I may employ in lieu of that shown in Fig. 1. It comprises inner and outer coils 70 and 71 having a cylindrical chamber 72 disposed centrally therein. Each coil communicates at its respective ends with the cylinder 72. Liquid working fluid is supplied through the conduit 39, as in Fig. 1, to the lower portion of the cylinder. The refrigerant vapor generated in both the cylinder and the coil is removed through the conduit 73 which has provided therein, below the level of the liquid, a small aperture 74 for the entrainment of liquid working fluid. The conduit 73 has a coiled portion 75 for the vaporization of the refrigerant contained in the entrained liquid.

Figs. 5 and 6 show different types of construction for housing the motor and the compressor. Fig. 5 comprises a base plate 80 having the motor casing 81 supported thereon. A casing for the compressor 82 is supported upon the motor casing and has cast integral therewith an upper bearing 83 for the driving shaft. In Fig. 6, the motor and compressor casing are provided in a common casting 91. An intermediate bearing plate 92 is provided between the motor and the compressor, a suitable gasket 93 making a fluid-tight joint with the casting 91. An end plate 94 is provided for the compressor.

While I have shown my invention in several forms, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

What I claim is:

1. In a refrigerating apparatus, the combination of an evaporator, a condenser, a compressor having suction and discharge ports, a casing communicating with the suction port of the compressor, and a removable receptacle disposed within the casing for receiving a quantity of vaporizable liquid refrigerant.

2. In a refrigerating apparatus, the combination of an evaporator, a compressor having suction and discharge ports, a condenser communicating with the discharge ports, a casing communicating with the suction ports, means interposed between the compressor and

the casing to permit the fluid to flow in a single direction only, that is, from the casing toward the compressor, and a removable receptacle disposed within the casing for receiving a quantity of vaporizable liquid refrigerant, whereby vaporization of the liquid refrigerant and its transmission to the condenser may be effected.

3. In a refrigerating apparatus the combination of an evaporator, a compressor for removing refrigerant vapor from the evaporator, a means for condensing refrigerant vapor discharged by the compressor, a motor for driving the compressor, a fluid tight housing for the motor, a removable container disposed within the motor housing for receiving a vaporizable liquid refrigerant, and communicating means provided between the motor housing and the inlet of the compressor, whereby vaporization of the liquid refrigerant and its transmission to the condensing means may be effected.

4. In a refrigerating apparatus, the combination of an evaporator, a compressor for removing refrigerant vapor from the evaporator, a chamber for condensing refrigerant vapor discharged by the compressor, a motor for driving the compressor, a fluid tight housing for the motor, removable access means provided in the motor housing, a container disposed within the motor housing for receiving a quantity of vaporizable liquid refrigerant, air outlet means provided in the condensing chamber, and communicating means provided between the motor housing and the inlet of the compressor, whereby vaporization of the liquid refrigerant and the transmission of air and refrigerant vapor to the condensing chamber may be effected.

5. In a refrigerating apparatus, the combination of a condensing chamber, a motor and a compressor disposed within the condensing chamber, a casing for the motor, said casing containing refrigerant vapor, an opening in the casing, a closure for the opening, a container disposed within the motor casing for receiving liquid refrigerant, communicating means between the motor casing and the inlet port of the compressor for removing air admitted to the casing and for vaporizing

the liquid refrigerant within the container, said compressor discharging into the condensing chamber, means provided in the communicating means between the motor casing and the inlet port of the compressor for preventing a back flow of the air and vapor during non-operation of the compressor, and means provided in the condensing chamber for purging off air discharged by the compressor.

6. In a refrigerating apparatus, the combination of a condensing chamber containing a body of refrigerant fluid, an evaporator, a conduit for conveying the refrigerant fluid to the evaporator, means for controlling the flow of the refrigerant fluid to the evaporator, and a float for actuating the controlling means, said float having its outer surfaces composed of a phenolic condensation product.

7. In a refrigerating apparatus in which a refrigerant fluid consisting of an intimate mixture of a refrigerant and a lubricant is employed, the combination of an evaporator including a coiled conduit and a substantially straight conduit of relatively large bore, means for passing liquid working fluid through the coiled conduit and through the straight conduit, means for conveying the refrigerant vapor generated in the coiled conduit to the straight conduit, refrigerant vapor outlet means provided in the straight conduit, and means for entraining a quantity of liquid working fluid in the refrigerant vapor passing through said outlet means.

8. In a refrigerating apparatus, the combination of an evaporator, a condenser, a compressor having suction and discharge ports, a motor for driving the compressor, a fluid tight housing for the motor, removable access means provided in the motor housing, a container disposed within the motor housing for receiving a quantity of vaporizable liquid refrigerant, air outlet means communicating with the discharge port of the compressor, and communicating means provided between the motor housing and the inlet port of the compressor.

In testimony whereof, I have hereunto subscribed my name this 2nd day of July 1923.

ANDREW A. KUCHER.
